(21) Appl. No.: **29/238,469**

(57) **CLAIM**

(22) Filed: **Sep. 15, 2005**

I claim the ornamental design for a cutting blade for a manual vegetable cutter, as shown.

(51) **LOC (8) Cl.** **07-04**

DESCRIPTION

(52) **U.S. Cl.** **D7/673**

FIG. 1 is a perspective view of a cutting blade for a manual vegetable cutter showing my new design;

(58) **Field of Classification Search** D7/672,

FIG. 2 is a plan view of the right side of the cutting blade of the invention;

D7/673, 677, 678, 693, 695, 381; 241/100,
241/95, 168, 169, 273.1–273.4, 274, 285.2;
30/247, 279.6, 280, 278, 286–291; 83/874,
83/856, 932, 954, 858, 717, 425.3, 431, 436.2,
83/697, 435.15, 437.7, 441.1, 698.11, 699.51,
83/699.61, 870, 167

FIG. 3 is a plan view of the left side of the cutting blade of the invention;

See application file for complete search history.

FIG. 4 is a plan view of the back of the cutting blade of the invention;

(56) **References Cited**

FIG. 5 is a plan view of the front of the cutting blade of the invention;

U.S. PATENT DOCUMENTS

FIG. 6 is a plan view of the bottom of the cutting blade of the invention; and,
